(57)

CLAIM

The ornamental design for a display screen with graphical user interface, as shown and described.

DESCRIPTION

FIG. 1 is a front view of a display screen with graphical user interface showing our new design; and,

FIG. 2 is a front view of the display screen with graphical user interface of FIG. 1 with disclaimed features removed for clarity purposes.

In FIG. 1, the broken line showing aspects of the graphical user interface forms no part of the claimed design. The outer broken line showing of the display screen forms no part of the claimed design.
